(No Model.)

J. R. BACK.

TOOL SUPPORT FOR LATHES.

No. 360,132.

Patented Mar. 29, 1887.

FIG. 1.

WITNESSES:
John R. Back
By Rufus B. Fowler
atty.

INVENTOR:

UNITED STATES PATENT OFFICE.

JOHN R. BACK, OF WORCESTER, MASSACHUSETTS, ASSIGNOR OF ONE-HALF
TO FREDERICK E. REED, OF SAME PLACE.

TOOL-SUPPORT FOR LATHES.

SPECIFICATION forming part of Letters Patent No. 360,132, dated March 29, 1887.

Application filed December 10, 1886. Serial No. 221,228. (No model.)

To all whom it may concern:

Be it known that I, JOHN R. BACK, a citizen of the United States, residing at Worcester, in the county of Worcester and State of Massachusetts, have invented a new and useful Improvement in Tool-Rests for Lathes, of which the following is a specification, accompanied by drawings, in which—

Figure 1 is a front view of a "chucking-lathe" with my improved tool-rest applied. Fig. 2 is a sectional view of the lathe-bed on line XX, Fig. 3, and showing a side view of the tool-rest. Fig. 3 represents a rear view of the tool-rest, and Fig. 4 is a detached view of the sliding latch by which the tool-rest is locked in position.

Similar letters refer to like parts in the several views.

My invention is applicable to any of the different forms of machines in which the operation of drilling, boring, chucking, or reaming is carried on, whether upright or horizontal; but in the accompanying drawings it is shown as applied to an ordinary form of what is known as a "chucking-lathe," which is represented in front elevation in Fig. 1, and in which A denotes the bed of the lathe, having the ways A' A². B is a revolving chuck attached to the live-spindle of the lathe, and C is a tool-holding turret revolving around a vertical axis, and mounted upon a table, C', having a sliding motion, by which the turret is moved toward or away from the chuck B. The construction and operation of these portions, however, are well known, and therefore require no detailed illustration or description.

Upon the rear side of the lathe-bed A, I form a way of any suitable form for the purpose required, and consisting in the present instance of the true vertical surface D, Fig. 2, having a T-shaped slot, D'. A carriage, E, having a tongue, E', entering the slot D', is arranged to slide along the way D in a line parallel with the ways A' A² of the lathe. Bosses 45 a a are formed on the carriage E, through which I pass the bolts b b, having heads c held in the T-shaped slots D', and binding-nuts d, by which the carriage E is clamped upon the way D in any desired position to suit the work 50 to be bored.

The carriage E is provided with lugs E², carrying the pintle E³, with its axis parallel with the way D and also with the axis of the revolving chuck B. Upon the pintle E³, I hinge the triangular frame F, having at its apex the socket F', to receive a collar or bushing, (not shown,) held in place by the set-screw e and adapted to fit the tool in use.

The frame F rests at F² upon the way A' of the lathe, so as to bring the center of the socket F' in alignment with the axis of the revolving chuck B. Through the front of the frame F, which extends beyond the edge of the way A', I place a bolt, G, having a washer, f, nuts f', and a tightening-nut, G', provided with a handle, G². Sliding upon the bolt G, between the washer f and the lower edge of the frame F, is a latch-plate, H, shown in section in Fig. 2 and in a detached view in Fig. 4, and having a bearing on opposite sides of 70 the clamping-bolt G or against the lower side of the frame at g, and also against the under side of the overhanging edge of the way A'. The open end of the slot h in the latch H is closed by the plate h', which prevents the entire removal of the latch when it is withdrawn from its engagement with the edge of the way A'. 75

When the tool-rest is not required, the nut G is loosened and the latch-plate H withdrawn, 80 and the frame F turned backward on the pintle E³ until the shoulder j is brought in contact with the similar and opposing shoulder, j', on the carriage E, thereby limiting the backward-swinging motion of the frame F and bringing the horizontal side F² into a vertical position, leaving the space between the chuck B and turret C unobstructed. 85

When the work requires the employment of the tool-rest, the carriage E is moved along 90 the way D in position to bring the frame close to the work held in the chuck B. The binding-nuts d are then tightened and the frame brought into the position shown in Fig. 2, with its front edge resting on the way A' of the lathe. 95 The latch H is pushed in beneath the overhanging edge of the way A' and clamped by tightening the nut G. A bushing or collar fitting the tool to be used is then placed in the socket F' and held by the set-screw e. The op- 100

eration of boring, drilling, chucking, or reaming is then carried on in the usual manner in machines of this class.

In case the work is made to revolve about a vertical axis, as in the different forms of "up-right" drilling or boring machines, the tool-rest may be attached to a carriage sliding in ways formed on one of the supporting posts or frame-work of the machine, the essential feature of my invention consisting in the use of a carriage sliding in a line parallel with the axis of the rotating work, and having a tool-rest hinged to the carriage, so the tool-supporting socket may be brought into alignment with the axis of the rotating work.

I am aware that tool-rests have been heretofore in use by which the tool has been supported in front of the work to be bored. Such I do not claim, broadly; but

What I do claim as my invention, and desire to secure by Letters Patent, is—

1. In a machine for boring, chucking, or drilling, the combination, with mechanism for holding the work to be bored, and mechanism for holding and presenting a cutting-tool to the work, and mechanism for rotating said work, substantially as described, of a tool-rest for supporting said cutting-tool between the work and the tool-holding mechanism, said rest consisting of a frame having a socket adapted to receive and support the cutting-tool, and hinged to a carriage longitudinally adjustable on the ways in a line parallel with the axis of said cutting-tool, and ways formed on the rigid frame-work of the machine and adapted to receive said carriage, substantially as described, and for the purpose set forth.

2. The combination, with mechanism for boring, chucking, or drilling, substantially as described, of ways formed on the rigid frame-work of the machine and parallel with the axis of the cutting-tool, a carriage arranged to slide on said ways; a frame hinged to said carriage, having a socket to receive and support the cutting-tool, and a surface formed on the rigid portion of the machine parallel with the way on which said carriage slides, and against which said frame is brought to secure a true alignment of the tool-supporting socket with the axis of the cutting-tool, substantially as described.

3. The combination, with mechanism for boring, chucking, or drilling, substantially as described, of ways parallel with the axis of the cutting-tool, a carriage arranged to slide on said ways, clamping devices, substantially as described, for binding the carriage on said ways, a frame hinged to said carriage and having a socket to receive and support the cutting-tool, and a surface formed on the rigid portion of the machine parallel with the axis of the cutting-tool, on which said hinged frame

rests when in use in order to secure the true alignment of said socket with the axis of the cutting-tool, substantially as described.

4. The combination, with mechanism for boring, chucking, or drilling, substantially as described, of ways parallel with the axis of the cutting-tool, a carriage longitudinally adjustable on said ways, a frame hinged to said carriage and having a tool-supporting socket, a way parallel with the axis of the cutting-tool, on which said hinged frame rests when in use, so as to bring said socket in true alignment with the axis of the cutting-tool, and a latching device attached to said frame, by which it is held on said frame-supporting way, substantially as described.

5. The combination, with mechanism for boring, chucking, or drilling, substantially as described, of ways parallel with the axis of the cutting-tool, a carriage longitudinally adjustable on said ways, a frame hinged to said carriage and having a tool-supporting socket, a way parallel with the axis of the cutting-tool, and on which said hinged frame rests, and a lip or shoulder formed on said hinged frame in position to be brought against an opposing surface on said carriage and maintain the hinged frame in an upright position when not in use, substantially as described.

6. The combination, with mechanism for boring, chucking, or drilling, substantially as described, of a way on the rigid portion of the machine for supporting a tool support or rest, a tool-supporting carriage resting on said way, and a latching device connected with said tool-rest and consisting of a sliding latch-plate arranged to engage the rigid portion of the machine, a bolt passing through a slot in said plate and held in said tool-rest, and a tightening-nut on said bolt, by which said latch-plate is clamped on said tool-rest, substantially as described.

7. The combination, with mechanism for boring, chucking, or drilling, substantially as described, of a way formed on the rigid portion of the machine parallel with the axis of the cutting-tool, a T-shaped slot in said way, a carriage sliding on said way and having clamping-bolts entering said T-shaped slot, a triangular frame hinged to said carriage and having a tool-supporting socket, a way formed on the rigid portion of the machine parallel with the axis of the cutting-tool, on which said triangular frame rests when in use, and a latching device consisting of a sliding latch-plate connected with said triangular frame by a bolt having a clamping-nut, substantially as described.
